UNITED STATES PATENT OFFICE.

LEWIS G. HOWLETT, OF BAY CITY, MICHIGAN.

CRANE TRUCK.

1,412,525.

Specification of Letters Patent. Patented Apr. 11, 1922.

Application filed March 19, 1919. Serial No. 283,486.

To all whom it may concern:

Be it known that I, LEWIS G. HOWLETT, a citizen of the United States, residing at Bay City, in the county of Bay and State of Michigan, have invented certain new and useful Improvements in Crane Trucks; and I do hereby declare the following to be a full, clear, and exact description of the invention, such as will enable others skilled in the art to which it appertains to make and use the same.

This invention relates to cranes for auto trucks and similar vehicles and pertains more particularly to an improved means for mounting the crane on the truck frame, whereby I am enabled to eliminate bending moments in the truck frame caused by the leverage exerted by the load, tending to overturn the mast of the crane and consequently—since the foot of the mast is rigidly secured to the frame—tending to buckle the frame at points near the foot of the mast.

The bending moments referred to are not bending moments produced by the dead weight of the mast and its load, but are the bending moments caused by the tendency of the load to overturn the mast when the load is suspended from the end of the boom.

With the foregoing and certain other objects in view, which will appear later in the specification, my invention consists in the devices described and claimed and the equivalents thereof.

In the drawings, Fig. 1 is a part diagrammatic side view of a truck equipped with a crane embodying my improvement, the boom of the crane shown in its fore-and-aft position.

Fig. 2 is an end position of the same with the boom swung out.

Fig. 3 is a detail of the mast and the lower end of the boom.

Fig. 4 is a part sectional view taken in a vertical plane through the head of the mast.

Fig. 5 is a similar view through the foot of the mast.

Referring to Figs. 1 and 2, 1 represents the truck frame and 2 the crane mast which is preferably of the self-supporting or pillar type, being made preferably in the form of a hollow truncated cone, the base of which is rigidly secured to its supporting platform, the base being sufficiently extended to firmly

support the mast without the use of guy ropes or guy extension rods, from the mast to the ends of the truck frame.

3 is a boom so mounted on the mast as to be capable of being swung from the fore-and-aft position of Fig. 1 to the fore-and-aft position of Fig. 2. The upper end of the mast is connected to the outer end of the boom by suitable cables 4. 5 is an outrigger and jack secured to the truck frame 1 to prevent the truck platform from tipping when the load is swung outboard, as shown in Fig. 2.

6, 6 are beams comprising a sill frame, to which the mast 2 is rigidly secured. This sill frame is also secured to the truck frame 70 and extends lengthwise thereof, from the mast to a point near the rear axle of the truck.

My improvement relates more particularly to this sill frame, its construction and mode of operation.

Referring to Fig. 1, in which the boom is shown in its fore-and-aft position and assuming that the boom is loaded, it is evident that the vertical thrust caused by the weight 80 of the crane and its load is carried by the truck frame 1. The tendency of the mast to overturn, due to the leverage of the load, can be counteracted in two ways—first, by connecting the top of the mast to the front 85 of the truck frame by guy ropes or rods; and second, by employing a mast of the self-supporting type, as shown in the drawing.

If guys are employed a bending moment 90 is introduced in addition to the bending moments caused by the weight. This second bending moment acts through the guy rope in the direction indicated by the arrow at A in Fig. 1, tending to spring the frame 1 at 95 a point near the base of the mast. When the self-supporting mast is employed, as shown in Fig. 1, no guy wire is used, but the tendency of the mast to overturn is resisted by the base of the mast, there being 100 a downward thrust on one side of the base and an upward pull on the other side, as indicated by the arrows at B, B'.

I have found in practice that when the base of the crane is secured to the truck 105 frame 1 direct that these forces B, B' tend to spring the frame. Since this tendency to spring the frame is caused by stresses ad-

ditional to the stresses due to the weight of the load, the capacity of the truck is considerably reduced.

I have found that this localized bending moment and tendency to buckle the frame can be easily removed by introducing the sill frame 6 between the base of the crane and the frame 1. This sill 6 is preferably made of beams of sufficient depth to resist 10 the buckling tendency caused by the forces B, B' and the length of the frame 6 is sufficient to distribute approximately uniformly, in the form of a distributed load, indicated by the arrows at C, and this load, 15 which is now in the form of a distributed load, instead of a localized bending moment, is easily carried by the frame 1 without tendency to buckle the frame. Consequently the capacity of the truck for carrying and handling heavy loads is greatly increased.

The mast may be made in any convenient manner, as shown in Fig. 3, where the shell 2, preferably made of sheet metal, is 25 mounted by a cap 7 carrying a ball thrust bearing 8 and side roller bearings 9. Upon these bearings rides a revolvable head 10 carrying sheaves 11 and tie rods 12. The lower ends of the tie-rods are secured to a 30 semi-cylindrical track 13 which partly encloses the base of the mast 2 and is adapted to travel around the mast when the boom is swung outwardly. To guide the track 13,

cylindrical ways 14 are provided near the bottom of the mast and suitable roller bearings 15 are interposed between the track 13 and the ways 14.

The boom 3 is pivoted as at 16 to the track 13.

By the means above described, I have provided a mounting for self-supporting mast cranes, especially adapted for use on auto trucks, whereby the bending moment in the truck frame produced by the eccentricity of the load is to a great extent eliminated, 45 in effect converted into a substantially uniformly distributed load, thereby enabling the truck to handle a very much heavier load with entire safety.

Having thus described my invention, what 50 I claim and desire to secure by Letters Patent is:

In combination, a motor truck chassis, a post crane, a pair of longitudinally extending sills secured to the base of said post 55 crane and adapted to resist the bending moment produced in the sills by the tendency of the post crane to tilt when under load, said sills extending lengthwise to support the side frames of said chassis, whereby 60 to deliver to said frames only the dead weight of the crane sills or load, without tending to distort said frames by bending.

In testimony whereof, I affix my signature.

LEWIS G. HOWLETT.
